CARBURETOR

Filed July 7, 1927

UNITED STATES PATENT OFFICE

SAÜL EMMANUEL MELKMAN, OF BRUSSELS, BELGIUM, ASSIGNOR TO THELMA CARBURETOR COMPANY, SOCIETE ANONYME, OF BRUSSELS, BELGIUM, A CORPORATION OF BELGIUM

CARBURETOR

Application filed July 7, 1927. Serial No. 204,071.

This invention relates to carburetors for internal combustion engines, and embodies certain improvements upon the structure shown, described and claimed in my pending 5 application, Serial No. 162,803, filed January 22, 1927.

In my prior application I have disclosed a carburetor structure in which the supply of fuel into the mixing chamber is controlled 10 by means of a suction operated, spring resisted valve, whereby an initially over-rich mixture is temporarily supplied into the explosion chamber of the engine in starting up the motor from rest, and thereafter the fuel supply 15 is controlled automatically by and proportionately to the suction action of the engine.

The present invention relates to carburetors of the same type, and its object is to 20 simplify and improve the structure and operation of devices of this nature and to provide a structure which is economical to manufacture and the parts of which can be easily and readily assembled, and wherein the disastrous 25 effects of back-fire are guarded against.

A further object is to provide means which are simple and efficient for applying and detachably securing the carburetor structure to the engine in connection with which it is to 30 be used.

Other objects of the invention will appear more fully hereinafter.

The invention consists substantially in the construction, combination, location and relative arrangement of parts, all as will be more 35 fully hereinafter set forth, as shown in the accompanying drawing, and finally pointed out in the appended claims.

The single view of the drawing is a longitudinal central section of an illustrative 40 form of carburetor embodying the principles of my invention.

In the illustrative structure shown, the carburetor body is comprised of the two hollow 45 cylindrical sections 3, 4, which are assembled and detachably secured together in endwise relation by any suitable means, such as the screws 5. Mounted within the section 4 is the Venturi tube 6, which may be held in place in any convenient manner, such, for ex-

ample, as by means of screw 7. Disposed transversely through the section 4 is a fuel supply tube 8, the respective ends of which, in the form shown, extending beyond the wall of the section 4. One of the extending ends of tube 8 affords means for connecting a fuel supply pipe 11 thereto, and the other affords means to receive and adjust a fuel supply control needle valve 13, the threaded end 13' of which is threaded into the bore of the tube 8. A screw head 17 permits the needle valve 13 to be adjusted. A screw cap 18, applied to and acting upon the tapered protruding end of tube 8, serves to clamp and hold the needle valve in its adjusted position.

The tube 8 not only serves as a supply conduit for the fuel, but it also provides a support for the tubular nozzle body 9. To this end a sleeve member engages over the tube 8, and is provided with an interiorly threaded socket 10, into which is screwed one end of the tubular nozzle body 9. This body 9 is formed with a chamber 12, which, when said body is screwed into supporting engagement with the socket 10, is brought into communication with the bore of tube 8, which is controlled by the needle valve 13. The interior chamber 12 is formed with an annular valve seat 16, with which coacts a valve 14, shown in this instance as a bell valve, which is normally urged to its seat by means of a spring 15.

The chamber 12 is prolonged beyond the valve seat 16 to form an auxiliary space or chamber 19 in the bore of the nozzle body 9. This space or chamber 19 is in communication with a mixing chamber 6', through an orifice or opening 20, which I will call the slow running fuel jet opening. The mixing chamber 6', communicates through an orifice 21 with an annular duct 22, which, in this instance, is shown as being formed in the exterior surface of the Venturi tube 6. The duct 22 communicates through a passage 23, 24, directly into the engine intake at a point beyond the usual throttle valve 25, as clearly shown.

The bore of the nozzle body 9 is provided at a point beyond or outwardly of the auxiliary space or chamber 19 with a cylindri-

cal portion 19', and outwardly of this cylindrical portion of the bore are located the orifices 31, which open communication from the bore of the nozzle body 9 into the region 5 of the narrowest portion of the mixing chamber 6 for delivery thereinto of the fuel. These orifices 31 constitute the main fuel outlets.

Mounted to slide longitudinally in the bore 10 of the nozzle member 9 is a valve rod having a cylindrical end portion 29 which works through the tubular portion 19' of the nozzle bore and extends into the auxiliary space or 15 chamber 19, in position to engage and lift the valve 14 from its seat when said valve rod is moved longitudinally into the nozzle bore. Adjacent the cylindrical portion 29 of the valve rod, said rod is formed with a slightly tapered portion 30, and outwardly 20 from said slightly tapered portion said rod is formed with a second portion 30' of greater degree of taper. These two tapering portions 30, 30' serve to regulate the extent of opening permitted for the supply of fuel 25 from the auxiliary space or chamber 19, through the tubular portion 19' to the main fuel outlet orifices 31. The stem portion 27 of the valve rod projects through the end closure cap 28 of the nozzle body 9, and has 30 adjustably mounted thereon a disk member 26, which works freely in a short passage 3', formed in the outer end portion of the section 3 of the casing. The disk member 26 controls the admission of outer air into the 35 interior of the casing and through the mixing chamber 6', to form part of the explosive charge to the engine.

In order to regulate and control the movements of the valve rod, I provide the outer 40 portion of the nozzle body 9 with a chamber 33', within which operates a collar 33, which is mounted to slide on the stem 27, and is engaged by a spring 34, which keeps it normally pressed against an abutment 32 on the 45 stem 27. A shoulder 35 forming the end wall of the chamber 33', forms a limit stop for the collar 33.

As will be readily understood, the suction 50 of the engine will cause the disk member 26 to be drawn into the open end of the casing member 3, to a greater or less extent according to the speed of the engine, thereby admitting a greater or less volume of air to the mixing chamber. The slight initial suction 55 action caused by starting the engine dis- places the valve member 26 and draws air into the mixing chamber. This movement of the valve member 26 is communicated to the stem 27, and hence the end portion 29 60 of the valve rod is caused to engage and unseat valve 14, and the slightly tapered portion 30 of said rod opens the passage 19', thereby admitting fuel to the orifices 20 and 31, and thence into the mixing chamber and 65 channels 22, 23, 24.

Should it be desired to supplement the suction action of the engine in actuating the disk member 26, or to independently actuate the same, I provide means for accomplishing that purpose, consisting, in this instance, of a flexible rod 36 arranged to be projected by button 37, or other suitable or convenient means, against the disk 26, when desired to effect the supply of fuel to the orifices 20, or 31, or both.

By opening the throttle 25, the suction action increases, thereby increasing the displacement of the disk member 26, and hence, also, of the valve rod actuated thereby. This increases the supply of fuel to the orifices 31. When the throttle 25 is closed, the reverse of this action takes place.

In case of back-fire, the expanding gases will act from inside the casing upon the disk member to move the same outwardly, thereby opening up instantly a wide exit path for said gases to the outer air and preventing damage or injury because of the explosion. The spring 34 will restore the valve rod and disk to their normal positions.

In applying a carburetor to a motor engine it is frequently necessary to rotatively adjust the carburetor to accommodate the lead of the fuel supply pipe connection 39. It is also desirable to secure the carburetor to the engine by an efficient joint connection, which not only affords, but also which maintains, a tight and efficient joint. In order to accomplish these results, I apply the end surface of the body portion 4 of the casing directly and tightly against the planed off surface of the boss on the engine which surrounds the intake opening. This application is effected by screwing an annular flange 38 onto the end of the casing 4, sufficiently to cause the end surface of the casing to extend beyond said flange, and then draw the entire carburetor body into its end surface seating against the planed surface of the boss by means of screw bolts passing through the flange, as clearly shown in the drawing. This not only ensures and maintains a tight joint, but it also permits axial adjustment of the carburetor body to accommodate any desired lead of the fuel supply pipe.

While I have shown and described only one practical embodiment of my invention, it is to be understood that my invention is capable of embodiment in various forms without departing from the scope or principles thereof. I do not desire, therefore, to be limited or restricted to the particular structure shown and described.

But what I claim as new and useful and of my own invention, and desire to secure by Letters Patent is—

1. In a carburetor construction a hollow body member having an air inlet and an air outlet passage, a throttle valve in said outlet passage, a tube supported in said body

with an adjustable fuel control valve therein, a tubular fuel supply body extending from said tube and in communication therewith, a ball valve in said tubular body having a seat, 5 a valve stem slidable in said tubular body and cooperating with a seat therein to form a valve, a slow running fuel orifice controlled by the ball valve and normal running fuel orifices controlled by the valve on said stem, 10 all formed in the tubular body and an air valve secured to said stem and located in the air inlet passage and means to adjust the position of the air valve, the initial movement of the air valve and stem opening the ball 15 valve to admit fuel through the slow running fuel orifice and on further movement to admit fuel through the normal running fuel orifices.

2. In a carburetor construction a hollow body member having an air inlet and an air outlet passage, a throttle valve in said outlet passage, a tube supported in said body with an adjustable fuel control valve therein, a tubular fuel supply body extending from said 25 tube and in communication therewith, a ball valve in said tubular body having a seat, a valve stem slidable in said tubular body and cooperating with a seat therein to form a valve, a slow running fuel orifice controlled 30 by the ball valve and normal running fuel orifices controlled by the valve on said stem all formed in the tubular body and an air valve secured to said stem and located in the air inlet passage, an air passage forming in 35 the body member and opening on the outside of the throttle valve at one end and at the other adjacent the slow running fuel orifice and means to adjust the position of the air valve, the initial movement of the air valve 40 and stem opening the ball valve to admit fuel through the slow running fuel orifice and on further movement to admit fuel through the normal running fuel orifices, the fuel flowing through the slow running fuel orifice after 45 mixing with air flows through said air passage in the body member.

In testimony whereof I affix my signature.

SAÜL EMMANUEL MELKMAN.
